ADVANCE MACHINE CO., OF CHICAGO, ILLINOIS, A CORPORATION OF ILLINOIS.

CHECK-DETECTOR FOR CHECK-ACTUATED MACHINES.

1,193,967.

Specification of Letters Patent.

Patented Aug. 8, 1916.

Application filed December 3, 1913. Serial No. 804,339.

REISSUED

To all whom it may concern:

Be it known that we, ALFRED D. ANTOINE and CLARENCE C. TRAVIS, citizens of the United States, residing at Chicago, in the 5 county of Cook and State of Illinois, have invented certain new and useful Improvements in Check-Detectors for Check-Actuated Machines, of which the following is a specification.

10 This invention relates to improvements in check detectors for use with check control mechanisms, automatic vending machines, or similar devices, which require the deposit of a check, to render the same operative, and one of the objects of the present invention is to provide an improved device of this character having means whereby the same may be operated when the proper check, or a check of predetermined character is deposited therein, but which will remain inoperative, when an improper check or other device is deposited therein and will operate to arrest such improper check or device.

25 A further object is to provide an improved device of this character having means for shifting or unseating the check when it has been moved to a predetermined position to prevent it from being returned 30 to the operator.

Other and further objects will appear from the following specification and claims, in connection with the accompanying drawings, in which:

35 Figure 1 is a rear elevation of an improved device of this character, constructed in accordance with the principles of this invention, with the rear wall of the casing removed and with the operating handle in 40 section, showing the disk and coöperating parts in normal position. Fig. 2 is a view similar to Fig. 1, showing in full lines the position the parts will assume when a check of the proper denomination or character is 45 placed in the check seat and the disk revolved, and also showing the parts in dotted lines in the positions they will assume when the disk is moved sufficiently to discharge the check. Fig. 3 is a view similar to Fig. 1, 50 showing the positions the parts will assume when the check disk is rotated without depositing a check in the seat. Fig. 4 is a view similar to Fig. 1 showing the positions the parts will assume when an improper

check is deposited in the check seat and the 55 disk advanced. Fig. 5 is a view similar to Fig. 1 showing the positions the parts will assume when a washer or apertured slug is deposited in the check seat and the disk advanced. Fig. 6 is a front elevation of the 60 rear plate of the casing. Fig. 7 is a rear elevation of an improved device of this class constructed in accordance with the principles of this invention. Fig. 8 is a sectional view taken on line 8—8 Fig. 5. Fig. 9 is a 65 transverse sectional view showing two thin checks in the device and the position they will assume with relation to the catch and to each other. Fig. 10 is an elevation of a portion of one of the catches, showing the 70 recess therein. Fig. 11 is a top plan view of the check seat showing the recess in the wall thereof.

Referring more particularly to the drawings, and in the present exemplification of 75 this invention, the casing within which the mechanism is housed consists primarily of a front plate 15 and a rear plate 16, the front plate 15 being preferably of a size slightly larger than the rear plate and being preferably provided with a circumferential flange within which the rear plate is arranged, and the two plates when assembled constitute the housing, having a check entrance opening 18 and a discharge opening 19, and the parts 80 of the casing are secured together in any suitable manner such as by means of the fastening devices 20.

Rotatably mounted within the casing thus formed is a disk 21, and by the use of the 90 term disk to be hereinafter employed in the specification and claims, is to be understood to mean any suitable check carrying element. This disk is provided with a check seat 22 opening through its periphery, and 95 is adapted to be rotated by means of a suitable handle 23 projecting beyond the face of the casing. The handle 23 preferably projects through the rear wall 16 of the casing, and connected thereto in any suitable 100 manner is an elastic element 24, which is anchored by its free end to a fixed support, and tends normally to move the disk in one direction, so as to cause the check seat 22 to register with the check entrance opening 105 18. Mounted within the recess 25, preferably in the front wall of the casing, and on one side of the disk 21 (see particularly

Fig. 8) is a catch 26 which is provided with a deflected portion or extremity 27, that is adapted to be projected into the opening of the check seat 22 of the disk 21, and an 5 elastic member 28, preferably in the form of a leaf spring is provided, and seated within another recess 27, beneath the catch 26, and is so arranged that it tends normally to move the extremity 27, in a direction to 10 enter the check seat, so that when a washer 30 is placed within the check seat and the disk rotated, the projection 27 will enter the aperture or opening in the washer (see Fig. 5) and thereby arrest the washer and the 15 movement of the disk 21.

Arranged adjacent the periphery of the disk is another catch 31 which is mounted for pivotal movement by its extremity 32 and is provided with a hooked extremity 33 20 adapted to enter the recess 34 in the periphery of the disk 21. The disk is also provided with a notch 35 adjacent the recess 34 and into which notch the extremity 33 of the catch 31 is also adapted to project, and 25 an elastic member 36, preferably in the form of a leaf spring is provided, which tends normally to move the extremity 33 or the notch 35 toward the periphery of the disk. This catch 31 is provided as additional 30 means for arresting the movement of the disk so that when a check of an improper size such as check 37 in Fig. 4 is placed within the check seat and the disk 21 is rotated, the extremity 33 of the catch 31 will 35 be moved by the elastic member 36, into the recess 34 of the disk when the recess is adjacent the extremity of the catch and thereby lock the disk against rotation to arrest the advancement of the check. Should 40 however, a check, other than a proper check, be deposited in the check seat, and which check is of a size to engage the face 38 of the catch 31, sufficiently to move the extremity 33 of the catch so that it will not 45 enter the recess 34, the catch will, just as soon as the check passes out of engagement with the face 38, move under the influence of the elastic member 36 to cause the extremity 33 of the catch to engage the notch 35 in the disk and thus lock the disk against 50 further advancement.

When a check of a proper size, such as check 39 in Fig. 2, is deposited in the check seat, the disk 21 may be rotated and during 55 the advancing movement the check will depress the catch 26 by engaging the projection 27 and the periphery of the check will engage the face 38 of the catch 31, to move the latter into the position shown in full 60 lines in Fig. 2 or into the position that the disk may be rotated sufficiently to permit the check 39 to be discharged from the check seat and out of the outlet or discharge opening 19 in the casing. During this rotation of the disk, a stress has been exerted

upon the elastic member 24, so that when the handle 23 is released after the check has been discharged, the stress of the elastic member 24 will rotate the disk in the opposite direction. 70

The stop 40 may be provided to extend from the face of the disk 21 to travel in a groove or way 41, in the plate 16 and this stop is adapted to coöperate with the shoulders 42, 43 of the groove or way, to limit the 75 extent of movement of the disk in one direction or the other. 75

In order to lock the disk 21 against retrograde movement, from each direction of movement of the disk, there is provided in 80 the present form of this invention, a reversible pawl 44, pivotally mounted as at 45 and controlled by an elastic member 46. This pawl is arranged so that its extremity 47 will be adjacent the periphery of the 85 disk, and the disk is provided with a series of peripheral notches 48 into which the pawl projects, and there is also provided a recess 49 in the periphery of the disk, which is preferably spaced from the recess 34, and 90 between which recesses 34, 49, the notches 48 are preferably arranged. In normal position, the pawl 44 assumes the position shown in Fig. 1. 90

Assuming now that a check of proper denomination is placed in the check seat, and the disk 21 is rotated in the manner already described, the pawl 44 will remain in the position shown in Fig. 1 until the recess 49 is 95 in a position to receive the extremity of the pawl, at which time the elastic member 46, will cause the pawl to assume the position 100 shown in Figs. 3 and 4. In this position of the pawl, and when the disk 21 is moved still farther in the same direction, the advancing 105 shoulder formed by the recess 49 will engage the pawl, and a still further movement of the disk in the same direction will cause the pawl to assume a position to point upwardly, or in a direction opposite to the direction to which it points in Figs. 1 and 5. 110 This will cause the extremity to enter notches 48 and thereby lock the disk against retrograde movement. The pawl will remain in this position with respect to the 115 disk until the recess 34 is moved into the position to receive the end of the pawl 44, which it will do when the proper check is carried by the disk, and at the time that the check seat 22 assumes a position or registers 120 with the outlet opening 19, the elastic member 46 will cause the pawl to then move into the recess 34, and by then reversing the direction of the movement of the disk, the pawl will be reversed into the position 125 shown in Figs. 1 and 5, when the pawl will again coöperate with the notches 48 to lock the disk against another and different retrograde movement. 130

In order to prevent the operation of the 130

device by the insertion of a thin check, the catch 31 is provided in the face of the portion 38 adjacent the periphery of the disk, with a recess 50, preferably arranged to one 5 side of the medial line of such face, so that the edges of the thin check will pass into this recess to prevent the catch 31 from being moved into a position that the extremity 33 thereof would not engage the

10 shoulder formed by the wall of the recess 34.

A similar recess 51 may be provided in the bottom of the check seat 22 and the recesses 50, 51 are preferably off-set laterally with respect to each other, so that in the 15 event of two thin checks 53, 53 being placed simultaneously in the check seat (see Fig. 9), the checks will be off-set with respect to each other, a portion of one check entering the recess 51 in the check seat, and a portion 20 of the other check will enter the recess 50 in the catch 30 so that the latter will not be tripped thereby.

To prevent the check from being returned to the operator, by a reverse movement of 25 the disk 21, after the check has been moved by the disk to a position that it has performed its proper function, a shoulder or projection 54 is provided. This shoulder or projection is arranged within the path 30 of movement of the check within the check seat so that when the check engages the shoulder, the latter will unseat or dislocate the check with respect to the check seat, so that upon a reverse movement of the 35 disk, the edge of the check will engage a shoulder 55, (see Fig. 6) and will thereby lock the check against return movement. This shoulder or projection 54 also serves as a means for ejecting the check from the seat 40 when it has been moved to a position adjacent the check discharging opening.

While in the present exemplification of this invention, the preferred forms and constructions have been herein shown and described, it will be understood that various 45 changes may be made therein without departing from the spirit of this invention.

What is claimed as new is:—

1. A device of the character described, 50 embodying a casing having a check entrance and a check discharge opening, a rotatable check carrier provided with a check receiving orifice, a normally inactive catch, said catch having a shoulder, means operating 55 to move the catch to cause the said shoulder to enter the check receiving orifice when the latter is positioned adjacent the shoulder and in the absence of a check in the orifice, an additional catch disposed between the casing and the periphery of the check carrier, and being also disposed entirely within the plane formed by the side faces of the check carrier, and a shoulder on the periphery of the check carrier and with 60 which shoulder the second recited catch co-

operates when the first said catch is inactive, a portion of the second recited catch projecting into the path of movement of the edge of the check in the receiving orifice.

2. A device of the character described, 70 embodying a casing having a check entrance and a check discharge opening, a rotatable check carrier provided with a check receiving orifice, a normally inactive catch, said catch having a shoulder, means operating to 75 move the catch to cause the said shoulder to enter the check receiving orifice when the latter is positioned adjacent the shoulder and in the absence of a check in the orifice, an additional catch disposed between the periphery of the check carrier and the casing and being also disposed entirely within the plane formed by the side faces of the check carrier, a shoulder on the periphery of the check carrier and with which shoulder the 80 second recited catch co-operates when the first said catch is inactive, a portion of the second recited catch projecting into the path of movement of the edge of the check in the receiving orifice, means tending normally to move the check carrier in one direction and means for moving the carrier in the opposite direction and against the stress 85 of the first said means.

3. A device of the character described, 90 embodying a casing having a check entrance and a check discharge opening, a rotatable check carrier provided with a check receiving orifice, a normally inactive catch, said catch having a shoulder, means operating to 95 move the catch to cause the said shoulder to enter the check receiving orifice when the latter is positioned adjacent the shoulder and in the absence of a check in the orifice, an additional catch disposed between the 100 periphery of the check carrier and casing and being also disposed entirely within the plane formed by the side faces of the check carrier, a shoulder on the periphery of the check carrier and with which shoulder the 105 second recited catch co-operates when the first said catch is inactive, a portion of the second recited catch projecting into the path of the movement of the edge of the check in the receiving orifice, means for rotating the carrier, and a stop device for limiting the degree of rotation of the carrier.

4. A device of the character described, 110 embodying a casing, having a check entrance and a check discharge opening, a rotatable check carrier provided with a check receiving orifice a normally inactive catch, said catch having a shoulder, means operating to 115 move the catch to cause the said shoulder to enter the check receiving orifice when the latter is positioned adjacent the shoulder and in the absence of a check in the orifice, an additional catch disposed between the periphery of the check carrier and the casing and being also disposed entirely within the 120

125

130

plane formed by the side faces of the check carrier, a shoulder on the periphery of the check carrier and with which shoulder the second recited catch coöperates when the 5 first recited catch is inactive, a portion of the second recited catch projecting into the path of movement of the edge of the check in the receiving orifice, and interengaging means between the carrier and casing for 10 limiting the extent of the rotation of the carrier.

5. A device of the character described, embodying a casing having a check entrance and a check discharge opening, a 15 rotatable check carrier provided with a check receiving orifice, a normally inactive catch, said catch having a shoulder, means operating to move the catch to cause the said shoulder to enter the check receiving orifice 20 when the latter is positioned adjacent the shoulder and in the absence of a check in the orifice, an additional catch disposed between the periphery of the catch and the casing and being also disposed entirely within the 25 plane formed by the side faces of the check carrier, a shoulder on the periphery of the check-carrier and with which shoulder the second recited catch coöperates when the first said catch is inactive, a portion of the 30 second recited catch projecting into the path of movement of the edge of the check in the receiving orifice, and an additional shoulder on the carrier and with which the second recited catch coöperates under predeter- 35 mined conditions.

6. A device of the character described, embodying a casing having a check entrance and a check discharge opening, a rotatable check carrier provided with a check receiving 40 orifice, a normally inactive catch, said catch having a shoulder, means operating to move the catch to cause the said shoulder to enter the check receiving orifice when the latter is positioned adjacent the shoulder and in the 45 absence of a check in the orifice, an additional catch disposed between the periphery of the check carrier and the casing, a shoulder on the periphery of the check carrier and with which shoulder the second recited 50 catch coöperates when the first said catch is inactive, a portion of the second recited catch projecting into the path of movement of the edge of the check in the receiving orifice, said catches operating transversely with respect to each other, and an ejector operating 55 to dislodge the check with respect to the receiving orifice.

7. A device of the character described, embodying a casing having a check entrance and a check discharge opening, a rotatable check carrier provided with a check receiving orifice, a normally inactive catch, said catch having a shoulder, means operating 60 to move the catch to cause the said shoulder to enter the check receiving ori-

face when the latter is positioned adjacent the shoulder and in the absence of a check in the orifice, an additional catch disposed between the periphery of the check carrier and the casing, a shoulder on the periphery of the check carrier and with which shoulder the second recited catch coöperates when the first said catch is inactive, a portion of the second recited catch projecting into the path of movement of the edge of the 70 check in the receiving orifice, to be engaged and moved by the check, and provisions whereby an improper check will pass said portion without moving the last said catch. 75

8. A device of the character described, embodying a casing having a check entrance and a check discharge opening, a rotatable check carrier provided with a check receiving orifice, a normally inactive catch, said catch having a shoulder, means operating to 80 move the catch to cause the said shoulder to enter the check receiving orifice when the latter is positioned adjacent the shoulder and in the absence of a check in the orifice, an additional catch disposed between the 85 periphery of the check carrier and the casing, a shoulder on the periphery of the check carrier and with which shoulder the second recited catch coöperates when the first said catch is inactive, a portion of the second recited catch projecting into the path of movement of the edge of the check in the receiving orifice to be engaged by the check, said catches operating transversely with respect to each other, and one of the catches projecting 90 over the other, and provisions whereby an improper check will pass said portion without moving the catch, the said provisions embodying a recess in one of the coöperating 95 parts into which a thinner check will project. 100

9. A device of the character described, embodying a casing having a check entrance, and a check discharging opening, a disk rotatable in the casing and having a check 110 seat, a plurality of yielding catches controlled by the check, said catches crossing each other and operating transversely with respect to each other, one of the catches having a portion projecting into the path of the 115 seat, the other catch having a portion adjacent the path of movement of the edge of the check in the seat, and being provided with a recess in its adjacent face and into which recess checks of a size less than a predetermined thickness will project. 120

10. A device of the character described, embodying a casing having a check entrance, and a check discharging opening, a disk rotatable in the casing and having a check 125 seat, a plurality of yielding catches controlled by the check, said catches operating transversely with respect to each other, one of the catches having a portion adapted to project into the seat, the other catch having 130

a portion adjacent the path of movement of the edge of the check in the seat, and being provided with a recess in its adjacent face to one side of a medial line of such face and 5 into which recess checks of a size less than a predetermined thickness will project.

11. A device of the character described, embodying a casing, having a check receiving and a check discharging opening, a disk 10 rotatable therein and having a check seat, and a plurality of yielding catches controlled by the check, operating transversely with respect to each other and one of which catches has a portion adjacent the path of movement 15 of the edge of the check in the seat, the wall of the check seat being provided with an open recess and into which recess a check of a size less than a predetermined thickness will project.

20 12. A device of the character described, embodying a casing having a check entrance, and a check discharging opening, a disk rotatable in the casing and having a check seat, and a yielding catch having a portion 25 of its surface adjacent the path of move-

ment of a check in the seat, the said surface and the wall of the check seat being provided with opposed recesses of a width less than the width of the said surface and the 30 wall of the check seat.

13. A device of the character described, embodying a casing having a check entrance, and a check discharging opening, a disk rotatable in the casing and having a check 35 seat, and a yielding catch having a portion of its surface adjacent the path of movement of the check in the seat, the said surface and the wall of the check seat being provided with opposed recesses, said recesses being off-set laterally with respect to each 40 other.

In testimony whereof we have signed our names to this specification, in the presence of two subscribing witnesses, on this 29th day of November A. D. 1913.
